UNITED STATES PATENT OFFICE.

ORLANDO G. DARLING AND HENRY A. SCHULZ, OF BROOKLYN, N. Y.

TRUSS.

SPECIFICATION forming part of Letters Patent No. 293,230, dated February 12, 1884.

Application filed February 24, 1883. (No model.)

To all whom it may concern:

Be it known that we, ORLANDO G. DARLING and HENRY A. SCHULZ, both of Brooklyn, in the county of Kings and State of New York, 5 have invented a new and useful Improvement in Trusses, of which the following is a full, clear, and exact description.

Reference is to be had to the accompanying drawings, forming a part of this specification, 10 in which similar letters of reference indicate corresponding parts in all the figures.

Figure 1 is a sectional elevation of our improvement, shown as applied to a one-side direct-acting single truss. Fig. 2 is a front elevation of the same, parts of the hoop being 15 broken away. Fig. 3 is a sectional elevation of the same, taken through the line *xx*, Fig. 2.

The object of this invention is to promote 20 convenience in wearing trusses, and prevent the said trusses from causing pain or discomfort to the wearer by pressure upon the back or sides.

The invention relates to a truss made with a back-pad provided with a ball-and-socket 25 joint for connecting the said pad with the truss-hoop, so that the said pad can adjust itself to the movements of the wearer, and can thus be worn with comfort, as will be hereinafter fully described.

30 We will describe our improvement as applied to a one-side direct-acting single truss, but do not limit ourselves to such use, as it can be applied with equal advantage to other trusses and supporters.

35 A represents the spring or hoop of a truss, which is provided with a front pad, B, attached to one end of the said hoop, and a leather strap, C, attached to its other end and perforated to receive the screw or knob attached to the first end, or to the pad-holder for 40 securing the truss to the wearer adjustably.

D is the back-pad, which is made long and narrow. The middle part of the face of the back-pad D is concaved, and its end parts

slightly convexed, as shown in Fig. 1. The 45 middle part of the back of the pad D projects, and is recessed to receive the ball E, which is secured in the said recess by a plate, F. The plate F is concaved upon the inner side to fit upon the ball E, is perforated to receive the 50 shank of the said ball, and is secured to the back of the said pad D by screws. The shank of the ball E is secured to the slide G, through which the hoop A passes, and which is secured to the said hoop A by a set-screw, H, 55 so that the back-pad D can be readily adjusted by loosening the said set-screw H. With this construction the concavity in the face of the pad D causes the said pad to fit easily upon the back of the wearer, and the ball-and- 60 socket joint E F, by which the said pad is connected with the hoop A, allows the pad to adjust itself to the various movements of the body of the wearer without friction, so that the truss can be worn with comfort for long 65 periods of time, and does not have to be removed after a short time on account of pain caused by pressure and friction upon the back and sides.

We are aware that a spring bar and convex 70 pads have been used in a truss, but are not aware that the pads have ever been placed diametrically opposite to each other, or the back-pad made in the form which we have described.

75 What we claim as new and of our invention is—

A truss consisting of the spring A, the convex pad B at the front and connecting by its stem the two ends of the spring, and the concave rear pad, D, ball-jointed to an adjustable sleeve on the spring, as shown and described.

ORLANDO G. DARLING.
HENRY A. SCHULZ.
